United States Patent Office.

JOHN A. WOOD, OF FAR ROCKAWAY, NEW YORK.

Letters Patent No. 105,023, dated July 5, 1870.

IMPROVEMENT IN SAWING-MACHINE.

The Schedule referred to in these Letters Patent and making part of the same.

To all whom it may concern:

Be it known that I, JOHN A. WOOD, of Far Rockaway, in the county of Queens and State of New York, have invented a new and useful Improvement in Hand Circular-sawing Machine; and I do hereby declare that the following is a full, clear, and exact description thereof, which will enable others skilled in the art to make and use the same, reference being had to the accompanying drawing forming part of this specification.

The object of this invention is to furnish a simple and effective machine for sawing in wood-shops, and for joiners' work generally; and

It consists in the arrangement and combination of parts hereinafter described.

In the accompanying drawing—

Figure 1 represents a top or plan view.

Figure 2 is a vertical section of fig. 1 on the line $z-z$.

Figure 3 is a detail of the upper table.

Figure 4 is a detail of the lower table.

Similar letters of reference indicate corresponding parts.

A is the frame by which the operating parts of the machine are supported. This frame is made of wood, and of any desired size and strength.

B is the driving-shaft, which extends across the frame, with a crank, C, on one end, for driving the machine, and a fly-wheel, D, on the other end.

E is a gear-wheel on this shaft, which meshes into a pinion, F, on the saw-shaft G.

H is a fly-wheel on the outer end of the saw-shaft.

I is the main table, for splitting or sawing boards or other lumber.

Just above this table is an adjustable feed-roller, J, which is revolved by means of a band, K, on the cone-pulleys L and M, as seen in fig. 1. Cone-pulleys are used so that the feed may be varied according to the thickness of the wood to be sawed.

In the middle of this feed-roller there is a section of it, N, fluted or serrated, to give it a hold upon the board or wood to be sawed.

This feed-roller operates in connection with a loose

roller, O, directly beneath, on which the board to be sawed rests.

P is the upper table, which rests on the lower one, and is, consequently, raised and lowered with it. This table is used for rebating, and for all the purposes to which it is adapted.

Both tables are provided with adjustable guides, R and S, as seen in the drawing.

The tables are raised and lowered, or adjusted, by means of double inclined planes, T and U, as seen in fig. 2.

These inclined planes are moved by the crank-screw V.

The frame W of the lower table rests on the inclined planes.

The table is lowered by withdrawing the plane, as it descends by its own gravity.

Each table has rollers, X, at each end of the table-frame W, which are on a level with the tables over which the lumber to be sawed is fed. The upper table is readily removed when not wanted for use.

The tables may be adjusted to cut any desired depth, and the feed may be varied to suit any thickness of stuff, or any degree of power.

For slitting up boards or planks, and preparing cabinet or joiners' work, this machine will be found of the greatest advantage.

Having thus described my invention,

I claim as new and desire to secure by Letters Patent—

1. The combination of the tables I and P and the inclined planes T and U in a machine for sawing, arranged and operating substantially as described.

2. The loose friction-roll O, placed in a vertically-adjustable table, P, combined with a fluted roll, N, all relatively arranged in a sawing-machine, to form an improved feeding device, adapted to different thicknesses of wood.

The above specification signed by me this 24th day of February, 1870.
